CLOSURE FLANGE-CONTAINER WALL COMBINATION

Richard L. Parish, Jr., North Salem, N. Y., and Frank Zampella, Ridgefield, N. J., assignors to American Flange & Manufacturing Co. Inc., New York, N. Y., a corporation of Delaware

Application July 14, 1953, Serial No. 367,830

5 Claims. (Cl. 285—45)

This invention relates to closure flanges for container wall openings and to combinations of the same with container walls and is particularly concerned with closure flange-container wall combinations where the container walls are formed from sheets coated exteriorly or interiorly or both.

Steel shipping containers, particularly in the category of steel barrels and drums, have developed over the years and have been made so that they are now a well recognized and most essential package for the shipment of a variety of commodities. They have found a wide market in the shipment of commodities which had no effect on or are not affected by the steel out of which they are made. So useful and effective have they proven themselves that a demand has arisen for the fabrication of such containers with interior coatings to protect commodities against corrosion, contamination, etc., and the industry has found such coatings which can be effectively employed.

Since almost the inception of the light weight steel drum it has been the recognized practice to coat the exteriors thereof for protection of the steel and for the imparting of distinctive and attractive appearances thereto. For many years this has been done by the painting or lacquering of the drums after they were formed. The results are reasonably satisfactory but this method of coating calls for considerable work, equipment and floor space due to the necessity, among other things, of applying the lacquer to the finished drums, baking those drums in ovens and then, in addition, or alternatively, conveying the drums for considerable distance through the air to allow the lacquer to set. Efforts to similarly coat the interiors of assembled drums, particularly if they are not of the removable head type, involve so many additional factors that the results achieved hardly warrant the effort involved.

In recent years at least one manufacturer developed exterior coatings which could be applied to flat sheets prior to the fabrication of them into drums and which resisted marring and fracture from the steps involved and equipment employed in the forming of such sheets into drums. More recently, coatings, designed for the interior linings of drums, and the application of them to flat sheets, have been developed to withstand the forming of the sheets into drums without marring or fracture. Certain of these coatings, like the exterior coatings just mentioned, not only adhere well to the metal but are also tough. Others, such as Saran, adhere well to the metal and are good coatings for preventing the contact of food products with the metal of the container, but are rather easily fractured.

The application of closure flanges or bushings to openings in such coated sheets and the forming of the sheets to receive them have involved troublesome problems. The perforating and embossing of such sheets, in manners heretofore practiced, and the action of securing existing closure flanges in such perforations could not be followed where the sheets were pre-coated either exteriorly or interiorly or both, without the likelihood of scuffing or frac-

2

turing the coating. When the coating on the outside of the drum is scuffed or broken, it is unsightly and the metal is likely to be exposed to corrosion. Thus the full effectiveness of the coating is lost and the quality of the product is reduced. When the coating on the interior of the drum is badly scuffed or broken the drum becomes worthless as a coated container, for the contents, such as food products and chemicals, are likely to come in contact with the metal and be contaminated by it. Thus a great demand has arisen for closure flanges and applying methods which can be employed without introducing these causes of rejection of the drums as a marketable product.

Applicants have met this demand and solved the problem in a straightforward economical manner. They have done so while at the same time enabling the manufacture of closure parts and the application of them to container walls to be carried on without departing materially from pre-existing practices and without involving material changes in manufacturing or applying machinery, with which latter all the drum manufacturers throughout the world are equipped. Furthermore, the closure flanges of the invention enable the application thereto of closure plugs and capseals in manners comparable to those to which the workers in the art are accustomed.

It is accordingly a primary object of the invention to improve upon closure flanges for and the application of the same to container walls.

Another primary object is to provide such closure flanges for and the application of the same to coated sheets to be employed in the forming of containers.

Another object is to provide such flanges for and the application of the same to sheets used in the forming of container walls without marring the coating on either the interior or exterior thereof.

Still another object is to provide such closure flanges which will not contaminate the contents of lined shipping containers or be contaminated by such contents.

A further object is to provide such closure flanges formed for the reception of closure members which closure members will likewise avoid contamination of the contents of the container.

A still further object is to provide such closure flanges and the application of the same to container walls so formed and applied that the containers, of which they form part, will be useable for the shipment of non-contaminating commodities after the container has been considered to be no longer useable for the shipment of products subject to contamination.

Further and more detailed objects of the invention will in part be obvious and in part be pointed out as the description of the invention, taken in conjunction with the accompanying drawing proceeds.

In that drawing:

Fig. 1 is an elevation partly broken away and shown in section of a closure flange in accordance with the invention.

Fig. 2 is a top plan view thereof.

Fig. 3 is a view, similar to Fig. 1, of the retaining collar for use in conjunction with the flange of Fig. 1.

Fig. 4 is a top plan view thereof.

Fig. 5 is a bottom plan view of a fragmentary portion of the flange base.

Fig. 6 is a top plan view of a section of container wall stock perforated and embossed to receive the flange of Fig. 1.

Fig. 7 is a section thereof taken on lines 7—7 of Fig. 6.

Fig. 8 is an assembly view, partly in elevation and partly broken away and shown in section of the flange of Fig. 1 secured in place in the container wall opening of Fig. 7 and including the retaining collar of Fig. 3.

Fig. 9 is a similar view with the addition of a plastic protecting ring around the base of the flange.

Fig. 10 is a front elevation partly broken away and shown in section of a complete plastic over-lay for the flange of Fig. 1.

Fig. 11 is a top plan view thereof.

Fig. 12 is an elevation partly broken away and shown in section of the assembly of flange, over-lay, drum-stock and retaining ring, placed together ready for application but prior to the applying action.

Fig. 13 is a similar view after the insertion action has been completed.

Fig. 14 is a bottom plan view on smaller scale of the construction shown in Fig. 13.

Fig. 15 is a view, similar to Fig. 13 of a complete closure including screw threaded closure plug and capseal; and

Fig. 16 is a view, similar to Fig. 15, showing the threaded neck portion of the over-lay removed, leaving a portion surrounding the base of the metal flange and with a plug received in the metal flange and a capseal thereover.

The closure flange, as shown in Fig. 1, generally comprises a base 1 and an upstanding neck 2. The base 1, preferably circular in outline, has a series of upstruck projections 3 formed out of the stock thereof. These projections extend part way up the outer surface of the neck 2 as well as extending outwardly therefrom. Preferably these projections are formed by a stamping, or coining, operation, with the result that the under surface of the base 1 is recessed as shown at 4. The flange base 1 extends outwardly from the projections 3 to a substantial extent as shown at 5.

The neck 2 is interiorly threaded throughout a substantial portion of its height, as seen at 6 and is reamed at 7 above those threads, for a purpose which will appear hereinafter. No particular number of projections 3 is considered as necessary, but for a flange presenting an internal diameter of a 2" pipe thread, as shown at 6, a round number of eight projections is suitable. Similarly, of course, the drum stock 8, as shown in Fig. 7, is perforated at 9 with an opening of a diameter to receive the exterior surface of the neck 2. The opening 9 is also provided with the appropriate number of recesses inset at 10 to snugly receive the corresponding number of projections 3. In addition, the container wall stock 8 is embossed, outwardly of the recesses 10, into an upwardly extending rib 11. The rib 11, as seen in Fig. 8, is positioned to substantially overlie the outer rim of the flange base 1.

The retaining collar, shown in Figs. 3 and 4 has a top portion 12 of cylindrical form, whose interior diameter is substantially the same as the exterior diameter of the neck 2, and has a lower outwardly flared portion 13. The extent of the collar is such that the end edge 14 of the portion 13 seats against the inner side of the rib 11, adjacent the base thereof, as seen in Fig. 8, when the retaining collar is assembled with the flange and the drum stock. The inner surface of the flared portion 13 carries a gasket 15. This gasket is formed of material preferably applied in the fluid state, allowed to set and adhering to the metal of the collar.

It is, of course, to be appreciated that the flange of this invention may be effectively employed for bordering the openings in steel containers whose walls are devoid of both inner and outer coatings. Next they are useable for containers having pre-coated outer wall surfaces but where such walls are devoid of any interior coating and where no problem of contamination of the contents of the container by the raw metal of the flange or of the container wall exists. The application of the flange to such unlined container is illustrated in Fig. 8. There it will be seen that the flange neck 2 has been inserted up through the opening in the container wall with the projections 3 fitting up in the recesses such as 10. The collar member 12 overlies the neck 2 and has its end edge 14 engaged with the inner surface of the rib 11. The top portion 5 of the flange base is secured up against the upper surface of the drum stock inward of the rib 11 and is held up thereagainst by the curling or beading outwardly of the por-

tion 7 of the flange neck over the upper end of the collar 12. This action, at the same time, serves to force the collar 12 tightly against the rib 11 so that the flange is clamped hard on to the drum stock. The gasket 15 will prevent any possible leakage between the wall 5 of the flange base and the undersurface of the drum stock. The flange is thus in a position to receive a closure plug therewithin and a capseal thereover, in the manner illustrated in Fig. 16.

Positive prevention of the turning of the flange, with regard to the drum stock, is provided. Any effort of the projections 3 to escape from the recesses of the drum stock in which they seat is guarded against by the engagement of the end 14 of the collar with the drum stock closely adjacent the base of the recesses 10 while the flange is held tightly against the drum stock by the interaction of it with the collar 12. The rib 13 assures that such interaction will be a tight one by precluding any tendency of the collar to spread outwardly with respect to the drum stock. The only part of the drum stock whose exterior surface coating might be marred lies within the collar 12 so cannot be seen.

In some instances the making of the flange out of materials impervious of the action of the contents of the container provides a solution for the closure problems of containers having internal linings or coatings. Illustrations of this are where the flange is made of stainless steel or aluminum rather than ordinary steel. Nevertheless provision must be made for preventing the container contents from reaching the raw edges of the drum stock around the opening 9 and for preventing the fracturing of the inner coating in a position where the contents of the container can get at the metal beneath that coating.

Protection against these possible causes of trouble is here provided by the use of a ring of suitable plastic material around the base of the flange. This ring, shown at 16 in Fig. 9, is generally U-shaped in cross-section, having a base portion 17 and inwardly extending rims 18 and 19, which overlie the top and bottom surfaces of the flange for a short distance inward from the edge so that, initially, the ring will stay on.

When this flange is applied to the container by a pressing and curling operation, the same as that of Fig. 8, the rim 19 of the collar 16 is secured up tightly within the recess 20 beneath the rib 11. Thus any likelihood of the container contents coming in contact with the ordinary steel of the drum stock, at places such as raw edges 9 and 10, is precluded by the gasketing action of the rib 19. Furthermore, it is to be noted the inner coated surface 21 of the drum wall 8 is somewhat below the upper surface 5 of the flange skirt. This constricts the opening between the edge of the flange skirt and the recess 20 so that the rib 19 is precluded from squeezing out as the securing of the flange is effected. On the contrary, the tendency is for the material of the rib 19 to be squeezed inwardly. From this showing it is apparent that if the container contents are such that they can be protected against contamination by the use of the proper material for the making of the flanges, then this assembly will meet all the requirements.

Where it is necessary or desirable to isolate the metal of the flange from the contents of the container, that can be done by the application of the over-lay, shown in Figs. 10 and 11, to the flange as shown in Figs. 12 through 15. This over-lay member would preferably be made of some suitable plastic material of reasonable rigidity, yet of adequate flexibility to assure self-gasketing, while, at the same time, being as inert with respect to the contents of the container as would the lining material 21 for the container wall. Polyethylene is a good illustration of a material suitable for this purpose.

The over-lay member here illustrated, generally indicated at 25, has a main neck portion 26 whose outer surface 27 is such that it will tightly engage the screw threaded portion 6 of the flange neck and will flow around

the peaks of the threads sufficiently to form a partial engagement therewith. The upper end of the overlay neck 26 is provided with an outwardly extending annular ledge portion 28 which lies against the normal gasket receiving surface provided at the upper end of the threads 6 and by the outward curling of the portion 7. This engagement, along with that of the partial engagement of the threads 6 and the portions 27, is sufficient to hold the overlay neck up within the flange neck while they are being applied to the container wall together and thereafter while the overlay is in use.

The interior of the neck 26 of the over-lay is formed with screw threads 29 throughout the major portion of its height and with a gasket receiving seat 30 at the upper end thereof. These formations effectively receive a closure plug in tight engagement therewith and for forming a leakproof joint therewith, such plug being illustrated in Fig. 15.

From the bottom end of the neck 26 the over-lay extends outwardly at 31, across the undersurface of the base of the flange, upwardly at 32, past the periphery thereof and inwardly as a rib 33 similar to the rib 19 of Fig. 9. Obviously then, all surfaces of the metal flange capable of coming in contact with the contents of the container and contaminating the same are covered and protected by means of the over-lay.

When it is desired to secure a metal flange, as heretofore described, equipped with such an over-lay in place in a container wall opening, the first step is to apply the over-lay to the flange. This, assuming that the over-lay is made of sufficiently flexible material, can be achieved by flexing the portions of the over-lay sufficiently to work the neck 26 up within the flange neck 2 and flexing the portions 32 and 33 outwardly sufficiently to work the flange base 1 therewith. If needed the over-lay can be heated somewhat to soften it and make it easier to work.

Another way of proceeding would be to mold the over-lay in place the flange, forming it with the threads and other active portions thereof while that is being done. By proceeding in this manner the over-lay would embrace the flange even more snugly, for the material of the over-lay would flow fully into the threads of the metal flange rather than doing so only partially as is the case where the over-lay is applied in cold state.

Assuming the over-lay to be in position on the flange, as illustrated in Fig. 12, the flange is then seated in the drum stock perforation, with the collar 12 overlying its neck 2 and with the projections 3 registered with the recesses 10. Then, by suitable press action, the base of the flange, with its over-lay, is forced up under the drum stock so that the rib 33 seats up in the recess 20 and is forced tightly therewith. At the same time the reduced upper end 7 is tightly curled over the upper end 12 of the collar, to hold the whole assembly in tight engaged relation. This forces the collar 12 and 13 tightly down against the outer surface of the rib 11 at the position 14 and this, of course, incorporates the reverse action of holding or pulling the flange and its over-lay up against the undersurface of the drum stock surrounding the perforation therethrough.

The rib 33 is held up tightly within the recess 20 and is blocked from flowing out therefrom by the constriction of the opening between the upper edge of the flange base and the wall of the recess 20. Furthermore, the material of the rib 33 is tightly compressed within the recess 20, prevents any leakage past the same towards the raw metal of the drum stock edge and also performs the important function of serving as a cushion between the metal flange and the drum stock to prevent fracture of the coating or lining 21.

The tightness of the securing is indicated by the fact that the material of the portion 31 of the over-lay is forced up into the recesses 4 in the under surface of the flange base as illustrated at 34 in Fig. 14. This serves, along with the tight securing at the position of the rib

33 and other inter-engaging features of the flange and over-lay, to prevent the rotation of the over-lay with respect to the flange and thus with respect to the container wall. Hence fracture of the coating by the turning of the over-lay thereagainst is precluded. The flange being positively precluded from rotating with respect to the drum stock through the inter-action between the projections 3 and the recess 10, disruption of the lining by rotation of any parts secured thereagainst is definitely precluded.

The closing of the opening through the over-lay 25 is illustrated in Fig. 15. Here a closure plug 35 is threaded at 36 into the threaded portion 29 of the over-lay neck 26. This closure plug may be of the same material as the over-lay or may be different therefrom, so long as it is sufficiently resistant to the action of the contents of the container. This plug, preferably being of a somewhat resilient plastic material, is formed into a suitable gasketing portion 37 at the upper end of its threads 36, which gasketing portion is engaged with the gasket seat 30 of the over-lay. Above that the plug is provided with an outwardly extending shoulder 38 terminating in a reduced lip 39 which partly overlies the beaded over portion 7. Suitable wrench engaging means are formed in the top of the plug extending downwardly into the body thereof, so that it can be turned up tightly with its gasket portion 37 engaging the gasket seat 30. When this is properly done a tight leakproof joint will result and the closure will be fully effective.

As an additional safeguard against the possibility of leakage, this closure will preferably be provided with a capseal 40. This cap has a generally disc-like top, bordered by a downwardly recessed portion 41, part of which engages the lip 39 and forces it against the portion 7, the other part of which carries its own gasket 42. The gasket 42 is preferably flowed in place within the capseal and fills the space above the bead 7 under the recess 41. The capseal 40 is secured in place by the downward drawing and inward crimping of its skirt portion 43 against the collar portion 12 beneath the bead 7. Such a capseal is provided with suitable score lines for the intended destruction of it but is proof against undetected tampering prior to such destruction. It is also leakproof. Thus a closure of additional high effectiveness results when such a capseal is used in conjunction with the plug 35.

When the lining on the inner surface of the drum stock 8 has become worn out, or fractured, or for other reasons it is decided that the interior coating aspect of the container is no longer desired, the overlay can be readily removed, facilitating the use of the drum for commodities not contaminated by the metal of the flange. Thus a larger flange opening is available for closing in conventional manner, as illustrated in Fig. 16. Here the portion 31 of the over-lay has been cut through at 44 and the neck portion 26 of the over-lay has been removed. Since, however, the portions 32 and 33 of the over-lay still remain, the tightness of the flange is in no way affected.

The plug for closing the opening in this flange consists of a threaded body 45 having a gasket seat 46 carrying a suitable gasket 47 which is secured in leak-tight engagement against the inner portion of the reduced end 7 as indicated at 48. The plug head 49 also engages that surface at 50, so that the gasket 47 is confined by metal once it is properly engaged. Again a suitable capseal 51 may, if desired, be secured over the plug. The top of this capseal has a reduced periphery 52 against which a gasket 53 is flowed in for engagement with the upper portion 7 when the capseal is applied. This capseal is also secured in place by the downward and inward drawing of the skirt 54 against the portion 12 of the collar.

While the preferred embodiment of the invention is shown and particularly described herein, it is to be understood that such showing is for illustrative and not limiting purposes as changes may readily be made without de-

parting from the spirit or scope of the invention. Without limitation of the foregoing it is to be noted that precise details of construction, such as the provisions for preventing relative rotation or for the securing of the flange and container wall together, as well as the particular materials suggested for use in the making of various parts, are included for illustrative and not for limiting purposes.

The invention accordingly comprises the features of construction, combinations of elements and arrangement of parts, all of which have been exemplified in the foregoing, and the scope of the application of which will be indicated in the claims.

Having described our invention, what we claim is new and desire to obtain Letters Patent for is:

1. In container construction, a container wall formed with an opening therethrough, a plurality of recesses and with said neck extending through said opening formed in the stock of said container wall and extending outwardly from said opening, an upstanding rib formed in said container wall stock around said opening, said rib having an inner downwardly inclined face and said rib being spaced outwardly with respect to the bases of said recesses, a closure flange including a neck for extending through said opening, a plurality of projections for engaging said recesses and a base portion for underlying said wall adjacent said opening, said flange being assembled with said container wall with said projections engaging said recesses and a collar member overlying a portion of said flange neck extending through said opening, said collar member extending between the inner downwardly inclined face of said rib and the upper portion of said flange neck for securing said closure flange in place in said opening, the lower portion of said collar member being flared outwardly and a gasket member secured to the inner surface of the outwardly flared portion of said collar member.

2. In container construction in combination, a container wall formed with an opening therein, a closure flange received in said opening, said closure flange including a base engaged with said container wall on one side of said opening and a neck extending upwardly through said opening beyond the opposite side thereof, said neck and the border of said opening being in engagement and being formed with mated projection and recess portions to prevent rotation of said flange with respect to said container wall, said container wall being formed with an annular upstanding rib surrounding said opening and spaced outwardly from the border thereof, and providing a downwardly sloping surface inclined toward said

45
50

opening, a securing collar overlying said upwardly extending portion of said neck, said securing collar being flared outwardly around the bottom thereof, the free end of said outwardly flared portion engaging said downwardly sloping surface of said rib, the upper end of said collar and said flange neck being interengaged to hold said neck up in said opening and said collar downwardly against said inner surface of said rib, and a gasket secured to the inner surface of the outwardly flared portion of said collar, said gasket, in the securing of said collar in place about said flange neck, being compressed against the outer surface of said container wall stock and into the corner between the outer surface of said container wall stock and said flange neck about said opening.

15 3. In container construction, a container wall formed of rigid metallic material, said container wall being formed with an opening therethrough, and being upwardly off-set around said opening outwardly spaced therefrom to form an annular groove in the underside of said wall and an upstanding rib on the upper side thereof, said rib providing a downwardly and inwardly inclined surface, a metallic closure flange formed with a base portion and an upstanding neck portion, said closure flange assembled with said container wall with said base portion underlying said wall about said opening and overlying a major portion of said groove, said neck portion extending upwardly through said opening, a gasket seated in said groove and trapped therein by said base portion and a collar overlying said neck on the outer side of said container wall, said collar being engaged at its upper end with said neck and being flared outwardly adjacent its lower end with the free end of said flared portion engaging said downwardly and inwardly sloping inner surface of said rib to keep said closure flange assembled with said container wall and said gasket compressed in said groove.

4. Construction as in claim 3 and including said gasket forming part of an annular member U-shaped in cross section, said U-shaped member overlying the periphery of the base portion of said closure flange.

5. Construction as in claim 4, wherein said U-shaped member has a collar portion extending up within said flange neck.
